UNITED STATES PATENT OFFICE

100,501

DESIGN FOR A PORTABLE RADIO CABINET

John R. Morgan, Oak Park, Ill., assignor to
Sears, Roebuck and Co., Chicago, Ill., a corpora-
tion of New York

Application May 25, 1936, Serial No. 62,823

Term of patent 14 years

To all whom it may concern:

Be it known that I, John R. Morgan, a citizen
of the Republic of Guatemala, residing at Oak
Park, in the county of Cook and State of Illinois,
have invented a new, original, and ornamental
Design for a Portable Radio Cabinet, of which
the following is a specification, reference being
had to the accompanying drawing, forming a part
thereof.

Fig. 1 of the drawing is a perspective view of
a cabinet embodying my new design, showing
the front, side and top thereof;

Fig. 2 is a top plan view of the same; and
Fig. 3 is a rear elevation thereof.

I claim:

The ornamental design for a portable radio
cabinet, as shown.

JOHN R. MORGAN.
